UNITED STATES PATENT OFFICE.

JAMES CHARLES POTTER, OF PAWTUCKET, RHODE ISLAND, ASSIGNOR TO POTTER & JOHNSTON MACHINE CO., OF PAWTUCKET, RHODE ISLAND, A CORPORATION OF RHODE ISLAND.

AUTOMATIC CROSS-SLIDE-OPERATING MEANS.

1,034,506.

Specification of Letters Patent. Patented Aug. 6, 1912.

Application filed March 7, 1907. Serial No. 361,106.

To all whom it may concern:

Be it known that I, JAMES C. POTTER, of Pawtucket, in the county of Providence and in the State of Rhode Island, have invented 5 a certain new and useful Improvement in Automatic Cross-Slide-Operating Means, and do hereby declare that the following is a full, clear, and exact description thereof, reference being had to the accompanying 10 drawings, in which—

Figure 1 is a front elevation of a portion of an automatic turret lathe embodying my invention; Fig. 2 a rear elevation of the same; and Fig. 3 a cross-section.

15 The object of my invention is to simplify the construction and facilitate the adjustment of automatic cross-slide operating mechanisms, and to this end my invention consists in the mechanism constructed substantially as hereinafter specified and claimed.

To illustrate my invention I show it embodied in an automatic turret lathe of the class forming the subject of Patent No.

25 752,257, February 16, 1904, to Potter & Johnston Machine Co., in which lathe the turret-carrying slide A mounted upon the lathe bed or frame B is reciprocated by means of cam plates c secured to the periphery of a drum C, mounted upon a shaft D, and revolved by means of a spur gear c' attached to the drum, with which meshes a driving pinion d on a shaft D' receiving motion from some suitable source.

30 The cross-slide E is mounted in a guide block e on the lathe bed, and at the rear side of the machine is projected beyond said block, and is provided with a rack F on its underside, with which meshes a gear segment G on a rock shaft H journaled in bearings at the rear of the machine.

To rock the shaft to reciprocate the cross-slide automatically, said shaft is provided with a gear segment I, with which meshes a rack k on the rear end of a reciprocable bar K that extends toward the front of the machine, diametrically across the cam drum, and has at its end, at the front side of the machine, a projection or roller k' in the path of cam plates L, adjustably secured to the adjacent side of the drum C, which cams, by alternate engagement of the projection or roller, reciprocate the bar K, and thus rock the cross-slide actuating shaft to move the cross-

slide for feeding its tools to and from the 55 work, secured in the usual chuck M. The rear rack-carrying portion of the bar K passes over and is supported by a friction roller N, supported by a bracket attached to the bed of the lathe, and the forward portion of the bar K is slotted to pass over the drum shaft D, by which it is supported at this point. The cam plates L are secured to the drum C by means of bolts l and continuous, annular T-slots c² in the side of the 60 drum C. By the mechanism described, it will be seen that the reciprocation of the cross-slide is automatically effected.

For moving the cross-slide by hand, which is necessary for properly timing the action 70 of the cross-slide tools with reference to the turret tools, the cross-slide at its end at the front of the machine is provided with a rack O, with which meshes a pinion P on a shaft journaled in the cross-slide supporting 75 block e, and having a squared end for the application of a crank by which to revolve the pinion to move the cross-slide.

In adjusting the machine for work, the cross-slide actuating cam plates L are loosened, so that revolution of the cam drum C may not actuate the cross-slide moving bar K, and then, by means of a suitable crank applied to the shaft of the cross-slide operating pinion P, the cross-slide is moved to 80 place the cross-slide tool at the limit of the feed to be given it by its feeding cam L, and then the feeding cam L tightened in such position on the drum that its high point will engage the roller on the bar K, and the re- 85 turn cam L tightened in proper position to retract the cross-slide after the feed for cutting has been ended.

As the cam-engaging roller on the bar K is at the front side of the machine, the manipulations or adjustments of the cam plates L, which are made with reference to said bar roller, can be made by the workman at the front of the machine, and as the crank shaft for adjusting the position of the cross-slide by hand is also at the front of the machine, and close to the cam-carrying drum C, it will be seen that the adjustment of the machine can be accomplished without movement of the workman from the front of the machine, so that the time for adjustment of the machine is reduced to a minimum. The mechanism for automatically moving the

cross-slide is a simple one, especially since the means for transmitting motion from the cams L to the rock shaft segment I consist simply of the roller-carrying bar K.

5 Although I have shown and described my invention as embodied in a machine having certain details of construction, it is to be understood that my invention may be embodied in machines differently constructed.

10 Having thus described my invention, what I claim is—

1. In a lathe, the combination of a cross slide, a bar, operative connection between the bar and the cross slide, whereby movement of the bar is imparted to the cross slide and movement of the cross slide is imparted to the bar, a drum, cams adapted to coat with the bar to impart movement thereto, means connecting the cams and the drum 15 whereby the cams may be either fixedly secured to the drums or loosened therefrom, and means for operating the cross slide by hand independently of the cam operated connections.

25 2. In a lathe, the combination of a cross slide, a bar, operative connection between the bar and the cross slide, whereby movement of the bar is imparted to the cross slide and movement of the cross slide is imparted 30 to the bar, comprising a rock shaft, a gear connection between the rock shaft and the cross slide, and a gear connection between

the bar and the rock shaft, a drum, cams adapted to coat with the bar to impart movement thereto, means connecting the cams and the drum whereby the cams may be either fixedly secured to the drums or loosened therefrom, and means for operating the cross slide by hand independently of the cam operated connections. 40

3. In a lathe, the combination of a cross slide, a bar, operative connection between the bar and the cross slide, whereby movement of the cross slide is imparted to the bar, comprising a rock shaft, a gear connection between the rock shaft and the cross slide, and a gear connection between the bar and the rock shaft, the part of the bar engaged by the cams and hand operated means being at the front of the machine, a drum, 45 cams adapted to coat with the bar to impart movement thereto, means connecting the cams and the drum whereby the cams may be either fixedly secured to the drums or loosened therefrom, and means for operating the cross slide by hand independently of the cam operated connections. 50

In testimony that I claim the foregoing I have hereunto set my hand.

JAMES CHARLES POTTER.
